UNITED STATES PATENT OFFICE.

SIGMUND STERNAU, OF NEW YORK, N. Y.

DESIGN FOR A CHAFING-DISH.

SPECIFICATION forming part of Design No. 23,768, dated November 6, 1894.

Application filed October 6, 1894. Serial No. 525,179. Term of patent 3½ years.

To all whom it may concern:

Be it known that I, SIGMUND STERNAU, a citizen of the United States, residing in New York, county of New York, and State of New York, have invented and produced a new and original Design for a Chafing-Dish, of which the following is a specification, reference being had to the accompanying drawing, which shows the chafing-dish in perspective.

10 The leading or characteristic feature of my design is the body of the dish, having the outline or shape shown, provided with an upwardly and outwardly extending ring ornamented on the upper surface and a fanciful handle.

15

A is the body of the kettle, having the outline or shape shown, and provided with the outwardly extending ring a, bearing on its upper surface the ornamentation b. From the ring a extends the ornamented fanciful handle B.

C represents the cover or top and ornamented as at c, c.

What I claim is—

The design for a chafing dish as hereinabove shown and described.

SIGMUND STERNAU.
